(57) CLAIM

The ornamental design for a furniture article, as shown and described.

DESCRIPTION

FIG. 1 is a left side view of our new design for furniture article;

FIG. 2 is a top view thereof;

FIG. 3 is a bottom view thereof;

FIG. 4 is a front elevation view thereof;

FIG. 5 is a top front perspective view section of our new design for furniture article;

FIG. 6 is a partial cross section across line 6—6 of FIG. 1;

FIG. 7 is a top view thereof where each furniture top of FIG. 2 is rotated 90° and moved to the left; and,

FIG. 8 is a top view thereof where each furniture top of FIG. 2 is rotated 90° and moved to the right.

The broken lines are for environmental purposes only and form no part of the claimed design.
